UPDRAFT TRAVELING BLOWER FOR
CLEANING OVERHEAD SURFACES OF
ENCLOSURESGrover B. Holtzelaw, Charlotte, N. C., assignor to
Parks-Cramer Company, Fitchburg, Mass., a
corporation of Massachusetts

Application April 2, 1949, Serial No. 85,176

5 Claims. (Cl. 15—312)

1

This invention relates to improved apparatus for removing lint, dust, and other foreign substances from the ceiling, walls, and overhead obstructions of an enclosure, such as those of a room containing textile processing machinery from which lint, dust, and other foreign substances are carried by air currents and deposited upon the various surfaces and which, if allowed to accumulate, would drop in bunches upon the machines and the materials being treated, thereby interfering with the proper operation of the machines and affecting the uniformity of the product.

Traveling cleaners have heretofore been provided which are mounted upon tracks extending longitudinally over a series of textile machines and are provided with means for projecting currents of air downwardly upon the machines therebeneath and the material in process to blow the lint, dust, and other foreign substances away from the machines and deposit the same upon the floor. Traveling blowers with air blasts directed upward have been suspended from overhead tracks for the purpose of cleaning monitors, ceiling, and other surfaces relatively high up in the room.

The general object of this invention is to provide an apparatus for more effectively removing lint and other foreign substances from all upper surfaces of an enclosure, that is, not only the ceiling but portions of the side walls and all overhead obstructions such as lights, conduits, piping, shafting, motors, ducts, etc., by providing a traveling blower riding above a track located just above head height and constructed and operated to direct a strong blast of air over a large overhead area and in such a way that the various walls, ceiling, lights, and other overhead surfaces and objects will be reached progressively by air at different angles and at different intensities for more effective cleaning than has heretofore been possible by automatic means.

In some cases the traveling cleaning unit embodying the present invention is mounted upon a track which is supported from the machines being cleaned and associated with and connected to a traveling unit for projecting currents of air downwardly upon a series of machines therebeneath.

An important feature of the invention is that it permits the location of the overhead cleaner above the track on which it rides and in turn permits its blast of air to be directed quite uninterruptedly above the fan without restriction as to direction. Thus it is possible to mount the traveling unit above a relatively low track in-

2

stead of below a relatively high track as heretofore while keeping the entire installation above head height.

Another important feature enables additional thoroughness of cleaning to be secured by combining with the operation previously disclosed in overhead cleaners and with the optional additional intermittent back and forth linear movement of the whole traveling cleaner along the track the further novel movement of complete and continuous revolution of an inclined fan unit about a vertical axis which revolution likewise may be alternately in opposite directions.

The invention further provides a novel traveling blower unit for cleaning overhead surfaces and objects, suitable for mounting above a track, including a motor, means operable thereby for moving the unit along the track, a fan mounted for rotation on a vertically inclined axis in a vertically rotating housing for projecting a blast of air diagonally upward against the surface and objects, means for rotating the fan from the motor, and suitable means for continuously rotating the housing and thus revolving the fan in a complete circle about and on the said vertical axis. Thus the velocity, direction and wide coverage of the blast of air results from the combined effects of three separate movements, namely the rotation of the fan on its inclined axis, the revolution of the fan about the vertical axis, and the horizontal linear bodily movement of the unit along the track.

These and other objects and features of the invention will more fully appear from the following description and the accompanying drawings and will be particularly pointed out in the claims.

A preferred embodiment of the invention is illustrated in the accompanying drawings, in which,

Fig. 1 is a side elevation of a textile machine or series of aligned textile machines having a track mounted thereon and extending longitudinally thereof with a motor driven unit for projecting blasts of air downwardly upon the machines therebeneath and an independent unit connected thereto having a motor driven fan for projecting a current of air upwardly in a direction angular to the vertical, with means for automatically and continuously revolving the fan and its mounting about a vertical axis and having mechanism for simultaneously reversing the direction of travel of the connected units;

Fig. 2 is an end view of the construction shown in Fig. 1;

Fig. 3 is a diagrammatic plan view of the typical construction shown in Fig. 1;

Fig. 4 is a diagrammatic plan view of an alternative track arrangement illustrating parallel tracks mounted over aligned series of machines, the tracks being connected by curved sections to enable the units to travel continuously in the same direction and the means connecting the traveling units being such as to permit them successively to follow the curved sections of the track;

Fig. 5 is an enlarged plan view of the up-draft 10 cleaning unit the casing being broken away to show the mechanism for rotating the fan-supporting frame and the mechanism for driving the fan from the vertical shaft of the motor;

Fig. 6 is a side elevation of the construction 15 illustrated in Fig. 5, portions of the casing being broken away to illustrate the mechanisms therein.

The apparatus is illustrated diagrammatically in Figs. 1, 2, 3, and 4, as applied to a plurality of a series of aligned machines 1 having central posts 2 extending vertically upwardly from the machines in alignment and having at their upper ends brackets 3 which support parallel tracks 4. A motor driven unit 5 also may be mounted upon the tracks 4, and is provided with means for propelling itself or both units along the tracks and also with means for projecting blasts of air downwardly and transversely across the machines therebeneath.

The up-draft cleaning unit 6 embodying the present invention, when used in combination with unit 5, is spaced from the unit 5 and connected thereto by a rod 7 which is pivotally connected at its ends to the respective units and is adapted to maintain the units continuously in suitably spaced relation, and also to permit the units to pass around curved sections 8 connecting the ends of parallel tracks 4 supported over pluralities or series of aligned machines as shown in Fig. 4, or alternately to travel back and forth upon a straight track extending over a plurality of aligned machines as shown in Fig. 3, with means for reversing the direction of travel at each end of the track.

The up-draft traveling cleaning unit which is shown in detail in Figs. 5 and 6 comprises a carriage 9 having suitably spaced pairs of traction wheels 10 mounted on the parallel tracks 4. A vertical electric motor 11 is mounted upon the carriage 9 and has a vertical shaft 13 provided at its lower end with a worm 14 which engages a worm gear 15 for driving the shaft 17 and the wheels 10 thereon to propel the unit along the track.

A plate 18 mounted upon the upper end of the motor 11 is provided with a central upwardly extending boss 19 which forms a journal for the upper end portion of the motor shaft 13, the end of which 20 extends therethrough and has fixedly mounted thereon a pulley 21 of mechanism for driving the fan as hereinafter described.

The cylindrical boss 19 also provides an axle upon which is mounted the hub 22 of a circular spider 23 having a downwardly extending cylindrical flange 24 which is provided with internal teeth forming an annular gear. A rigid bracket which extends diametrically across the motor shaft has long and short end sections 26 and 27 which are respectively bolted to the spider 23 and an intermediate integral section 28 which is suitably inclined to the horizontal upon which the fan is so mounted as to direct the blast of air therefrom at such angle to the vertical that when the fan in its casing is revolved completely 75

about the vertical axis of the motor shaft, as hereinafter described, it will project the blast therefrom over a wide area of the surfaces to be cleaned.

5 A suitable bearing 29 for the fan shaft is provided with a flange 30 which is secured by bolts 31 to the inclined section 28 of the bracket. The fan 32 which is provided with a series of inclined blades is fixedly mounted upon the upper end of a shaft 33 which is journaled in the bearing 29 and is provided at its lower end with a pulley 34 which is driven by a belt 35 from the pulley 21 on the motor shaft. The belt 35 runs over intermediate pulleys 36 which are journaled on the respective ends of a shaft in a bracket 37 which is adjustably mounted upon the arm 26 of the bracket which extends diametrically over the motor shaft 13.

An angularly truncated casing 38 is secured 20 in circumferential relation to the cylindrical flange 24 of the annular gear 23 by bolts 38a surrounded by spacing sleeves 38b and encloses said gear, and the mechanism for driving the fan, and has at its lower end an outwardly 25 flanged bell-shaped mouth 40 through which air is drawn through the casing by the rotation of the fan 32. A skeleton guard 38x is mounted upon the top of the casing 38 and surrounds the fan.

Suitable means are provided for revolving the 30 fan and its support about the vertical axis of the motor. As illustrated herein this is accomplished by a gear 41 which meshes with the internal teeth 25 of the annular gear 23 and is fixedly secured upon the upper end of a shaft 42 which 35 is journaled in a long bearing sleeve 43 adjustably secured to the periphery of the motor 11 by the adjusting screw 44. The shaft 42 has secured to its lower end a circular frictional disk or wheel 45 which engages the side of one of the tracks 4 40 upon which the unit travels.

As the unit is propelled longitudinally of the track the frictional disk 45 drives the shaft 42 and through it rotates the gear 41 in such manner as to rotate the gear 23 and the mechanism 45 mounted thereon on the vertical axis 13 of the motor shaft.

When the unit is traveling in one direction the disk is a driving agent which serves to rotate the fan-supporting frame against the tendency of the fan to rotate it in the opposite direction. When the unit is traveling in the opposite direction both the fan and the disk contribute to rotating the fan frame, the disk also serving as a brake to determine the speed of rotation. At the same time the belt 35 through the pulleys 21, 36, and 34, drives the fan 32 at high speed. The blast from the fan is thus caused to sweep over a wide area of the surfaces to be cleaned. It is obvious that reversing the direction of travel of the unit along the track results 55 in simultaneously reversing the direction of rotation of the fan frame. These reversals are accomplished by operation of the automatic clutch hereinafter referred to, while the fan continues to rotate on its own axis in a single direction.

60 While in the preferred construction the inclined or diagonal direction to the vertical of the blast of air is secured by the inclined position of the fan, this inclined direction of the blast of air should not be restricted to this particular means for securing it. The essential feature is that the blast of air is directed upward at an angle inclined to the vertical and that this so inclined blast of air continuously revolves about a vertical axis thus sweeping over a wide overhead area at successively varying angles.

Usual means for supplying electric current to the motor of the traveling unit 5, when included, for projecting air downwardly upon the machines and to the motor of the up-draft cleaning unit 6 may be provided, or to the traveling up-draft cleaning unit alone in case it is only desired to clean the ceiling, walls, and overhead obstructions of the enclosure.

While the cleaning below and above the tracks is illustrated as separate units, it will be understood that the fans may be embodied in a single traveling unit driven by a single motor.

When either unit is mounted separately on a straight track, suitable known means are provided for reversing the direction of rotation of the traction wheels at the respective ends of the track such as a rod slidably mounted lengthwise of the carriage and extending at its ends beyond the respective ends of the carriage and adapted to engage suitable, preferably yieldable, abutments at the respective ends of the track and having clutch mechanism operated by the sliding movements of the rod when engaging an abutment to reverse the direction of rotation of the traction wheels. Meanwhile the fan which is operated from the motor shaft continues always to rotate in the same direction.

Similarly reversal of the direction of movements of both connected units for respectively cleaning surfaces of machines below the track and overhead surfaces of the enclosure and other surfaces above the track where the units are mounted upon a straight track may be simultaneously effected, as shown in Fig. 1. In such case the carriage of each unit has a rod 46 slidably mounted for movement longitudinally thereof and adapted to extend beyond the respective ends of each unit, means being provided for slidably moving the rods 46 of both units when the end of the rod of either unit engages the abutment at the end of the track.

In the preferred construction shown in Fig. 1 a rod 47, which is parallel to and preferably beneath the spacing rod 7 which connects the cleaning units, is slidably supported upon the rod 7 by suitable hangers 43. The rod 47 has at its respective ends an enlarged head 49 adapted to engage the projecting adjacent end of the sliding rod 46 of the respective traveling units so that when the end of the rod 46 of either unit engages the abutment at the end of the track the rods 46 of both units will be slidably moved simultaneously in a direction to cause reversal of the direction of rotation of the traction wheels of both units.

In such instances most satisfactory and economical operation of the up-draft traveling cleaner unit involves the use of a well-designed form of cushioned abutment mounted on the respective ends of the track for arresting the unit or units and causing reversal of the direction of travel thereof. A preferred form of abutment is illustrated in Fig. 1 and comprises a bracket having a standard 50 which is mounted on the end of the track and extends upwardly therefrom and has a tubular arm 51 extending over and suitably spaced from the track in parallelism therewith. A sleeve 52, which slidably fits the tubular arm and extends beyond the end thereof, is connected to or engages a vertically depending abutment plate 53 which is positioned in the path of and adapted to be engaged by the proximate end of the reciprocable rods 46 of a traveling unit as it approaches the end of the track. A coiled spring 54 which is enclosed in the sleeve 52 and

interposed between the abutment plate 53 and the end of the tubular arm 51 serves to cushion the impact of the rod 46 and the momentum of the traveling unit or units thereby avoiding the shock which might otherwise occur by abrupt arrest of the traveling units. It also serves to start the units back in the reverse direction.

In order to limit the reverse movement of the abutment plate produced by the spring 54 when a unit begins to travel in the reverse direction and to provide means for positioning the abutment plate properly for engagement with the ends of the rod 46, a horizontal U-shaped rod is slidably mounted in the standard 50 with one arm 55 extending axially through the tubular arm 51, the sleeve 52, and abutment plate 53, and provided at its end with a nut 56 adjustably engaging said plate. The other arm 57 of the U-shaped rod extends through a suitable hole in the standard 50 in parallelism with the arm 51 and through the abutment plate 53 and is provided at its end with a nut 58 which adjustably engages the abutment plate 53. When therefore the abutment plate 53 is engaged by the end of the rod 46 of the traveling unit the abutment plate will be forced against the resistance of the spring 54 yieldably to arrest the units, the rods 46 of the respective units will be moved longitudinally to cause reversal of the direction of rotation of the traction wheels thereby simultaneously reversing the direction of travel of the cleaning units.

It will be understood that in case of a layout as shown in Fig. 3 such a reversing means will be located at each end of the track.

When a unit begins to travel away from the abutment expansion of the spring 54 will force the abutment plate forwardly until the section 59 of the U-shaped rod which connects the parallel sections 55 and 57 thereof engages the vertical standard of the bracket and the abutment plate will then be properly positioned again to arrest and reverse the direction of travel of said unit or units.

While it is usual to employ such reversing mechanism at each end of straight track installations they also may be used temporarily at intermediate points on continuous track as shown in Fig. 4 to eliminate certain areas from the cleaning operation.

By reason of the present invention the combined effect of the rotation of the fan on an axis in inclined relation to the vertical axis of the motor and its revolution about said axis provides for cleaning wide areas of the surfaces of the enclosure, whether the track upon which the unit is mounted consists of one or more pairs of parallel tracks connected by suitable bends to provide a continuous track over the machines underneath, or a single straight track or plurality of connected tracks terminating in ends requiring the reversal of direction of travel of the cleaning unit. It is obvious that some extra effectiveness in overhead cleaning is secured when the automatic direction-reversing mechanism is utilized because in this way various overhead points are reached by the air blast intermittently at more different angles and intensities on successive trips of the traveling unit than if the unit were always to approach from the same direction.

It will be understood that the particular embodiment of the invention shown and described herein is of an illustrative character and is not restrictive of the meaning and scope of the following claims.

Having thus described the invention, what is claimed as new, and desired to be secured by Letters Patent, is:

1. An up-draft traveling blower unit, for removing lint and other foreign substances from the overhead surfaces of an enclosure such as a textile manufacturing department, mounted on and above a track in said enclosure, comprising a motor driven rotary fan, means acting to direct the blast of air from the fan upward at an angle to the vertical, and means for continuously revolving the air-directing means about a vertical axis while the fan is rotating and while the unit is propelled along the track thus to project the blast of air progressively over a wide overhead area and at successively different angles.

2. An up-draft traveling blower unit, for removing lint and other foreign substances from the overhead surfaces of an enclosure such as a textile manufacturing department, mounted on and above a track in said enclosure, comprising a motor, means connected to the motor for moving the unit along the track, a fan-supporting frame, means for rotating the frame continuously about a vertical axis, a fan mounted in the frame on an axis inclined to the vertical, and means for rotating the fan as it is bodily revolved by the frame about the vertical axis thereof thus to project the blast of air over a wide overhead area and at successively different angles.

3. An up-draft traveling blower for removing lint and other foreign substance from the overhead surfaces of an enclosure, comprising a unit mounted on wheels for traveling on a track in said enclosure, a motor, means connected to the motor for moving the unit along the track, a frame mounted to rotate on a vertical axis, a fan mounted on the frame to rotate on an axis inclined to the vertical acting to project a blast of air diagonally upward, means for rotating the fan from said motor, a wheel for frictionally engaging the track, a gear driven by said wheel, and an annular rack on and concentric with the axis of said frame driven by said gear acting to rotate the frame continuously and completely about its axis as the unit is propelled along the track.

4. An updraft traveling blower for removing lint and other foreign substance from the overhead surfaces of an enclosure, comprising a unit 50 for traveling on and above a track in said enclosure, a motor, means connected to the motor for

moving the unit along the track, a frame mounted to rotate on a vertical axis, an air-directing casing member projecting from the frame, a fan mounted to rotate on an axis inclined to the vertical and thus acting to project a blast of air diagonally upward, means for rotating the fan from the motor, an annular gear on the frame concentric with its axis, a friction wheel for engaging the track, a gear meshing with the annular gear of the frame driven by the friction wheel, with the said mechanism acting, as the unit travels along the track, to rotate the frame continuously and completely about its vertical axis and thus to revolve the fan about the said vertical axis and effect an efficient sweeping action of the air blast over a wide area resulting from the combined movements of the fan, the frame, and the unit as it travels on the track.

5. An updraft traveling blower for removing 20 lint and other foreign substance from the overhead surfaces of an enclosure, comprising a unit for traveling on and above a track in said enclosure, a motor, means connected to the motor for moving the unit along the track, a frame mounted 25 to rotate on a vertical axis, a fan mounted on the frame to rotate on an axis inclined to the vertical and thus acting to project a blast of air diagonally upward, a casing on the frame acting to direct the air to the fan, means for rotating 30 the fan from the motor, and means for continuously rotating the frame on its axis thus causing the inclined fan to revolve about said axis as the unit moves along the track with the said mechanism acting to effect an efficient sweeping action 35 of the air blast over a wide area resulting from the combined movements of the rotation of the fan on its inclined axis, the revolution of the fan about the vertical axis of the frame, and the linear travel of the frame on the track.

GROVER B. HOLTZCLAW.
